CLAIM

The ornamental design for a hybrid VTOL fixed-wing drone, as shown and described.

DESCRIPTION

FIG. 1 is a perspective top view of the hybrid VTOL fixed-wing drone;

FIG. 2 is a top view of the hybrid VTOL fixed-wing drone of FIG. 1;

FIG. 3 is a bottom view of the hybrid VTOL fixed-wing drone of FIG. 1;

FIG. 4 is a right view of the hybrid VTOL fixed-wing drone of FIG. 1; the left side view being a mirror image thereof; FIG. 5 is a left view of the hybrid VTOL fixed-wing drone of FIG. 1; the right side view being a mirror image thereof; FIG. 6 is a front view of the hybrid VTOL fixed-wing drone of FIG. 1; and,

FIG. 7 is a back view of the hybrid VTOL fixed-wing drone of FIG. 1.

The broken line showing of portions of the hybrid VTOL fixed-wing drone depicts environment and forms no part of the claim.

1 Claim, 7 Drawing Sheets(56)
